Ernest J. Randall
HIS ATTORNEY

UNITED STATES PATENT OFFICE.

CHESTER J. RANDALL, OF NAUGATUCK, CONNECTICUT, ASSIGNOR TO THE GOODYEAR'S METALLIC RUBBER SHOE CO., A CORPORATION OF CONNECTICUT.

APPARATUS FOR EXHAUSTING THE INTERIOR OF RUBBER ARTICLES.

1,199,420.

Specification of Letters Patent. Patented Sept. 26, 1916.

Application filed December 17, 1915. Serial No. 67,358.

To all whom it may concern:

Be it known that I, CHESTER J. RANDALL, a citizen of the United States, residing at Naugatuck, county of New Haven, and 5 State of Connecticut, have invented certain new and useful Improvements in Apparatus for Exhausting the Interior of Rubber Articles, of which the following is a full, clear, and exact description.

10 This invention relates to apparatus for applying low pressure or vacuum to the interior of a rubber article supported upon a substantially impervious form, and has for an object to provide a simple and effective 15 apparatus for enabling solid wood or other substantially impervious forms to be used in connection with the differential of pressure treatment of rubber articles of any type but especially those composed of a fabric lining 20 and an outer covering of rubber.

The differential of pressure treatment of such a rubber article comprises in a general way the steps of first building to substantially final shape the article composed of a 25 lining of fabric and an outer covering of vulcanizable rubber, supporting the article upon a correspondingly shaped form, and compacting the walls of said article prior to or during vulcanization by subjecting it to 30 an external pressure while communicating the fabric lining through the supporting form, which is hollow and perforated for this purpose, with fluid pressure lower than the pressure exerted on the outer covering. 35 This treatment has hitherto precluded the use of forms which were impervious or substantially so, such as for instance the solid wood forms upon which boots, shoes, etc., are built and vulcanized.

40 The present invention provides an apparatus designed especially to permit of substantially impervious forms being used in connection with a differential of pressure treatment, and to attain this end provides 45 essentially means for entering between and holding the article and the form apart and communicating the inner surface of the article with the source of low pressure or vacuum, as will be hereinafter fully 50 described.

The invention can be readily understood from the following description taken in connection with the accompanying drawing, in which the figure is a side elevation 55 partly in section showing an apparatus em-

bodying my improvements in operative position.

To specifically describe one type of apparatus suitable for carrying out the invention, I will describe the same in connection 60 with the manufacture of a rubber boot. The boot 10 is built up on the form 11 in the usual manner, the preferred type of form employed being a solid wood one which is impervious or substantially so, although 65 any other form which is substantially impervious may be employed. The boot is built up of an outer covering 12 of vulcanizable rubber or allied gum, and a lining 13 of fibrous material, preferably woven or knitted fabric, through the interstices of which the rubber may be most effectively brought into contact with the low pressure or vacuum of the differential of pressure treatment.

75 In carrying out the invention I preferably provide a metal cap 14 which is adapted to fit over the end of the boot form 11 inside of the edge of the boot preferably to be subsequently built thereon, the cap being provided with a tapered nozzle 15 adapted to fit over a correspondingly tapered nipple 16 of a vacuum or low pressure pipe 17. The metal cap comprises a vacuum chamber 18, a conduit 19, and an internal ledge 20 between the conduit and vacuum chamber. 80 The conduit is tapered from the vacuum chamber to its edge where it diminishes to nearly nothing and thus acts as a wedge to enter between and hold apart 85 the boot 10 and form 11 without mutilating either one. The flange 20 serves as a stop which engages the end of the form 11 and limits protrusion of the conduit between the 90 form and article.

95 To promote maximum efficiency of the vacuum or low pressure during application of the preponderating pressure on the outside of the article, a seal 21 is applied to lap the edge of the boot and form and assure a pressure-tight joint.

100 Although I have described but one embodiment of the invention, it is to be understood that this is merely illustrative of the invention, and various modifications 105 may be made within the scope of the claims without departing from the spirit or sacrificing any of the advantages of the invention.

Having thus described my invention 110

what I now claim as new and desire to protect by Letters Patent is:

1. Apparatus for applying low pressure or vacuum to the interior of a rubber article supported upon a substantially impervious form, comprising a vacuum or low pressure chamber, and means adapted to enter between and hold the article and the form apart and establish communication between the inner surface of the article and the chamber.
2. Apparatus for applying low pressure or vacuum to the interior of a rubber article supported upon a substantially impervious form, comprising a vacuum or low pressure chamber, a conduit adapted to enter between and hold the article and the form
3. Apparatus for applying low pressure or vacuum to the interior of a rubber article supported upon a substantially impervious form, comprising a cap adapted to fit over the end of the form between the edge of the rubber article thereon and means for operatively connecting the cap to a low pressure or vacuum device.

apart and establish communication between the inner surface of the article and the chamber, and a stop adapted to engage the form and limit entrance of the conduit between the form and article.

Signed at Naugatuck, Conn., this 4th day of December, 1915.

CHESTER J. RANDALL.
